UNITED STATES PATENT OFFICE

2,294,748

RIBBON FLAME BURNER

Hartwig Millard Hanson, Baltimore, Md., assignor to The C. M. Kemp Manufacturing Company, Baltimore, Md., a corporation of Maryland

Application July 24, 1940, Serial No. 347,122

8 Claims. (Cl. 158—104)

This invention is directed to a burner peculiarly adapted to presenting a stiff knife edge, blade like or ribbon like flame, the flame having a high temperature and burning with considerable pressure to the gas. In the production of such a flame in other burners than this construction, the velocity of the gas exceeds the rate of flame propagation with the result that the flame gets so far from the gas source that it is blown out by the force of the gas itself and it is a purpose of the present burner to produce such a ribbon like blast flame of high temperature that will not go out.

The burner is peculiarly useful in the soldering of tin cans, which are taken through a solder bath for soldering the side seams. The seams of such cans must be heated to a very high temperature so as not to extract heat from the solder bath and thereby cool it and yet this flame must be so narrow and restricted in its width as not to heat appreciably the can body away from the seam.

In the production of such can bodies, on modern machines, they come through at such a rapid rate that the burners heretofore constructed have either heated too much of the can bodies or they have not been able to heat them sufficiently to keep from extracting heat from the solder bath, through which they go.

Of course other uses of the burner in which a knife edge flame of very high temperature is required are met with frequently in the industry and this example is only given by way of illustration of the utility of the invention.

The burner of the invention is an improvement over the burner of the Patent No. 1,204,359 dated November 7, 1916, which has been tried and found not to produce sufficient heat in the time allowed by certain rapid manufacturing processes.

Other objects and advantages of the invention will be apparent from the following description and accompanying drawings, which form a part hereof, and in which:

Figure 1 is a top plan view of a burner embodying the present invention, with part of the top casting removed.

Figure 2 is a vertical sectional view of the burner.

Figure 3 is a side elevational view showing the multiple control valves.

Figure 4 is a cross-sectional view on line 4—4 of Figure 2.

Figure 5 is a cross-sectional view on line 5—5 of Figure 2.

Figure 6 is a similar view on line 6—6 of Figure 2.

Figure 7 is a partial inverted plan view of the top casting of the burner.

5 Similar numerals refer to similar parts in the several views.

The burner consists of an elongate body 1 made up of two castings, a top casting 2 and a bottom casting 3.

10 These two castings are permanently attached together by bolts 4. The top casting 2 has a trough 5 in its top section and in its bottom section a central longitudinally extending slot 6 and lateral longitudinal extending slots 7. Central slot 6 has spaced orifices 8 leading therefrom to the center of the trough 5. Lateral slots 7 have sloped passages 9 forming orifices at their top opening on each side of the orifices 8 in the bottom of the trough 5.

15 20 In the preferred construction the orifices 9 are arranged in staggered longitudinally extending rows as shown in Fig. 1, forming pilot flame orifices.

25 After cutting the slots 6 and 7 in the top casting 2, the lower portions of these slots are closed, the central one by plate 10 and the lateral ones by plates 11. Plate 10 is drilled so that it has alternately sloped spaced passages 12 and plates 11 are drilled to have sloped passages 13. These 30 sloped passages equalize the pressure of the fuel and cause the fuel in its flow to impinge upon the walls of the slots 6 and 7 to further equalize the pressure so that a fuel is presented to the burning orifices having a uniform pressure distribution.

35 The lower casting 3 has a centrally disposed chamber 14, when the castings are joined together, admitting fuel to the passages 12 and central slot 6. Fuel is fed to this chamber 14 through pipe 15 and it is controlled through valve 16. A baffle 17 is placed in the chamber immediately above the entrance to the pipe 15 to divert the flow of fluid to each end of the chamber and to prevent undue pressure imme-

40 45 50 40 through valve 16. A baffle 17 is placed in the chamber immediately above the entrance to the pipe 15 to divert the flow of fluid to each end of the chamber and to prevent undue pressure immediately above the pipe. Lateral chambers 18 are also in this lower casting and these, when the castings are connected, connect directly with lateral slots 7 in upper casting 2 through passages 13. These passages 18 are fed by a pipe 19 through side openings 20 drilled into the casting. As the casting is formed the fuel passes through opening 21 connecting the opening from pipe 19 with the openings 20 and the outer extremities of this opening 21 are closed by plugs 22. The flow of fuel through pipe 19 is con-

55

trolled by valve 23 and fuel passes through central pipe 24 to both valves 16 and 23.

By this construction a ribbon like blast flame may be projected from the central orifices 8 under great pressure and it may extend some distance from the trough 5 and the tendency of the flame to go out or be blown off because of the pressure of the fuel is prevented by the supporting lateral pilot flames burning with less pressure from orifices 9, these side flames being sloped toward the center flame to give it greater support in burning. The structure permits a center flame of continuous sheet or ribbon like formation substantially without perceptible division into separate jets and without high and low points or valleys and ridges, and as much flame and therefore heat as is possible is concentrated in a sharp knife-like line where it burns constantly. The concentration of heat is so great that one foot of this burner will supply as much heat as four or five feet of other available burners.

The separate control of the two flames allows for their accurate adjustment in relation to each other, and the main cut-off can be manipulated without disturbing that control when the burner 25 is shut down after use.

It will be apparent that modifications may be made in the apparatus to carry out the invention without departing from the principles thereof.

What is claimed as new and desired to be secured by Letters Patent is:

1. A ribbon flame burner comprising elongated integral orifice and fuel feeding sections and means to laterally connect said sections together to form a closed body having therein a centrally extending chamber and a central row of closely spaced orifices leading therefrom through said orifice section to the top thereof, and said body having therein interconnected lateral chambers extending one on each side of said central chamber and rows of closely spaced orifices in said orifice section on each side of and adjacent to said central row leading to the adjacent lateral chambers said fuel feeding section having therein a fuel inlet for said lateral interconnected chambers and a separate fuel inlet for said central chamber.

2. A ribbon flame burner comprising elongated integral orifice and fuel feeding sections and means to laterally connect said sections together to form a closed body said orifice section having in the top thereof an upwardly directed longitudinally extending trough, and said body having therein a centrally extending chamber and a central row of closely spaced orifices leading therefrom through said orifice section to the center of the said trough bottom and said body also having therein interconnected lateral chambers extending one on each side of said central chamber and rows of closely spaced orifices in said orifice section on each side of and adjacent to said central row in said trough leading to the adjacent lateral chamber said fuel feeding section having therein a fuel inlet for said lateral interconnected chambers and a separate fuel inlet for said central chamber.

3. A ribbon flame burner comprising elongated integral orifice and fuel feeding sections and means to laterally connect said sections together to form a closed shell having therein a chamber with longitudinally extending blast flame orifices leading therefrom through said orifice section to produce a substantially longitudinally continuous line blast flame, controlled means to admit fuel to said chamber through said fuel feeding

section and means to substantially equalize the fuel pressure through the length of said chamber, said shell also having a separate lateral chamber with pilot flame orifices passing therefrom through said orifice section to produce a pilot flame extending lengthwise of said blast flame and separately controlled means to admit fuel through said fuel feeding section directly to said lateral chamber.

4. A ribbon flame burner comprising elongated integral orifice and fuel feeding sections and means to laterally connect said sections together to form a closed shell having therein a central chamber with longitudinally extending blast flame orifices leading therefrom through said orifice section to produce a substantially longitudinally continuous line blast flame, controlled means to admit fuel to said chamber through said fuel feeding section and means to substantially equalize the fuel pressure through the length of said chamber, said shell also having lateral chambers on each side of and closed off from said central chamber with pilot flame orifices passing therefrom through said orifice section on each side of said blast flame orifices, to produce pilot flames extending lengthwise of said blast flame and means to admit fuel through said fuel feeding section directly to said lateral chambers.

5. A ribbon flame burner comprising elongated integral orifice and fuel feeding sections and means to laterally connect said sections together to form a closed shell having therein a chamber with longitudinally extending blast flame orifices leading therefrom through said orifice section to produce a substantially longitudinally continuous line blast flame, controlled means to admit fuel to said chamber through said fuel feeding section, said shell also having a separate lateral chamber with pilot flame orifices passing therefrom through said orifice section, the passages of said orifices being sloped inwardly toward the blast flame to produce a pilot flame extending lengthwise of and intercepting and joining said blast flame at a distance from said burner, and separately controlled means to admit fuel through said fuel feeding section directly to said lateral chamber.

6. A ribbon flame burner comprising elongated integral orifice and fuel feeding sections and means to laterally connect said sections together to form a closed shell having therein a chamber with longitudinally extending blast flame orifices leading therefrom through said orifice section to produce a substantially longitudinally continuous line blast flame, controlled means to admit fuel directly to said chamber through said fuel feeding section, and means in said chamber to substantially equalize the fuel pressure through the length of said chamber, said shell also having a separate lateral chamber with pilot flame orifices passing therefrom through said orifice section, the passages of said orifices being sloped inwardly toward the blast flame to produce a pilot flame extending lengthwise of and intercepting and joining the blast flame at a distance from said burner, and separately controlled means to admit fuel through said fuel feeding section directly to said lateral chamber.

7. A ribbon flame burner comprising elongated integral orifice and fuel feeding sections and means to laterally connect said sections together to form a closed shell having therein a central chamber with longitudinally extending blast flame orifices leading therefrom through said or-

fice section to produce a substantially longitudinally continuous line blast flame, controlled means to admit fuel to said chamber through said fuel feeding section, said shell also having lateral chambers on each side of and closed off from said central chamber with pilot flame orifices passing therefrom through said orifice section, on each side of said blast flame orifices, the passages of said orifices being sloped inwardly toward the blast flame to produce pilot flames extending lengthwise of and intercepting and joining said blast flame at a distance from said burner, and separately controlled means to admit fuel through said fuel feeding section directly to said lateral chambers.

8. A ribbon flame burner comprising elongated integral orifice and fuel feeding sections and means to laterally connect said sections together to form a closed shell having therein a central chamber with longitudinally extending blast 20

flame orifices leading therefrom through said orifice section to produce a substantially longitudinally continuous line blast flame, controlled means to admit fuel to said chamber through said fuel feeding section, and means to substantially equalize the fuel pressure through the length of said chamber, said chamber also having lateral chambers on each side of and closed off from said central chamber with pilot flame orifices passing therefrom through said orifice section, on each side of said blast flame orifices, the passages of said orifices being sloped inwardly toward the blast flame to produce pilot flames extending lengthwise of and intercepting and joining the blast flame at a distance from said burner, and separately controlled means to admit fuel through said fuel feeding section directly to said lateral chambers.

HARTWIG MILLARD HANSON.
